DETECTING DEVICE

Henry Laetari, Los Angeles, Calif., assignor to Roberts Manufacturing Co., Los Angeles, Calif., a corporation of California

Application November 24, 1952, Serial No. 322,240

11 Claims. (Cl. 1—102)

This invention relates to a detecting device which can be used in conjunction with an apparatus for inserting fasteners in a mounting strip to detect the absence of fasteners from said mounting strip after the apparatus has operated upon said strip to insert said fasteners therein, said detecting device being designed to de-energize the apparatus to permit the defective strip to be either removed from the apparatus for recirculation therethrough, or to be returned to a position wherein the missing fasteners can be inserted in the mounting strip.

As previously indicated, the present invention is designed to be utilized in conjunction with a fastener inserting apparatus and will be described as associated with a fastener inserting apparatus of the character of that more particularly described in copending application, Serial No. 263,096, filed December 24, 1951, now Patent No. 2,669,714 granted February 23, 1954, by Newcomb et al., entitled "Method and Apparatus for Producing Carpet Retaining Strip." However, although the detecting device is described as utilized in conjunction with the specific apparatus and designed to coact therewith, it is obvious that the principles of the invention can be utilized with apparatus of a markedly different character from that disclosed in the previously referred to application.

The primary function of the apparatus with which the device of the invention is associated is the insertion of a plurality of fasteners in a mounting strip, the fasteners normally projecting a substantial distance beyond one face of the strip to permit the mounting strip and its associated fasteners to be utilized in retaining flexible floor coverings such as rugs or carpets in predetermined position on the floors of rooms or other enclosures. During the passage of the mounting strip through the apparatus, the fasteners are driven into the mounting strip at predetermined intervals, the fasteners being fed to the strip by fastener feeding means which occasionally fails to feed a fastener to the face of the strip at the predetermined time which results in a hiatus or gap existing in the row or rows of fasteners which are normally found in the strip after its passage through the apparatus. Since the strips pass through the apparatus at relatively high speeds, visual detection of the absence of one or more fasteners from the large number of fasteners driven into the strip is relatively difficult and it would be extremely undesirable to provide prospective users with a mounting strip which was lacking the predetermined number of fasteners.

It is, therefore, an object of the invention to provide a detecting device which will automatically determine the absence of one or more fasteners from the mounting strip after the mounting strip has passed through the fastener inserting stage of the apparatus, said device incorporating means for indicating to the operator of the apparatus that an imperfect article has been produced by the machine which is lacking in the requisite number of fasteners.

As the mounting strips are fed through the apparatus with which the device of the invention is associated, it occasionally happens that a gap exists between adjacent ends of mounting strips being conveyed through the apparatus and, due to the gap between the mounting strips, the detecting device of the invention would be caused to function because the detecting device would detect no fasteners in the gap between adjacent ends of the two strips. Another object of the invention is the provision, in a device of the aforementioned character, of means which will temporarily inactivate the detecting device

2

when the absence of a mounting strip from the apparatus is discerned, or when a gap between adjacent ends of the mounting strips is perceived.

To enable the detecting device to function for its intended purpose, there is provided therein fastener detecting means which detects the presence of fasteners in the mounting strip and is responsive to the absence of one or more fasteners therefrom, said fastener detecting means being adapted, when the absence of one or more fasteners is determined thereby, to energize the device to de-activate the apparatus with which it is associated so that the defective strip may be removed from the apparatus or recirculated therethrough.

Also provided in the device of the invention is strip detecting means which detects the presence of a strip in the apparatus and which is responsive to the absence of a strip at a predetermined point in the apparatus so that when the absence of a strip at the predetermined point is detected, the strip detecting means will operate to prevent the fastener detecting means from energizing the device to cause the de-activation of the apparatus.

When the fastener feeding means fails to function properly, it is usually due to a blocking of the feeding means which results in the failure of the apparatus to insert fasteners in the strip during its passage through the apparatus. If the operation of the apparatus were continued, it is obvious that a large number of fasteners would not be inserted in the mounting strip in the predetermined sequence. Therefore, there is provided in the device of the invention de-energization means responsive to the activation of the fastener detecting means by the absence of one or more fasteners from the strip which will immediately, upon the detection of such absence of one or more fasteners, de-energize the entire apparatus so that the strip cannot be fed completely through the machine when the fastener feeding means is not functioning properly. In this manner, waste of time is eliminated since the defect is rendered apparent immediately by the cessation of operation of the apparatus with which the device of the invention is associated.

In the particular application with which the device of the invention is disclosed, the apparatus is designed to drive a plurality of fasteners into the strip in two rows, the fasteners in each row being spaced an equal distance from each other. It is a further object of the invention to provide fastener detecting means responsive to the absence of one or more fasteners from either of the rows of fasteners in the mounting strip. Furthermore, the fastener detecting means of the invention is so constructed that before one of the fasteners in either of the rows is disengaged the succeeding fastener in either of the rows will be engaged to prevent the inadvertent energization of the device by the detection of the gap between adjacent fasteners rather than the gap created by the absence of one or more fasteners.

Other objects and advantages of the invention will be apparent from the following specification and the accompanying drawings which are for the purpose of illustration only and in which:

Fig. 1 is a perspective view showing the device of the invention incorporated in a fastener driving and inserting apparatus;

Fig. 2 is a transverse, sectional view taken on the broken line 2—2 of Fig. 1;

Fig. 3 is a view similar to Fig. 2 showing the operating portions of the device in different positions from those shown in Fig. 2;

Fig. 4 is a front elevational view of the device taken from the broken line 4—4 of Fig. 2;

Fig. 5 is a transverse sectional view taken on the broken line 5—5 of Fig. 2; and

Fig. 6 is a fragmentary view taken from the broken line 6—6 of Fig. 5.

Referring to the drawings, and particularly to Fig. 1 thereof, there is shown a detecting device 10 constructed in accordance with the invention and utilized in conjunction with a fastener driving or inserting apparatus 11. The fastener inserting apparatus 11 includes a frame 12 which has mounted thereupon fastener driving and feeding means 13 for feeding and driving fasteners 14 into an elongated mounting strip 15. As best shown in Figs. 1-3, the fasteners 14 are arranged in longitudinally

oriented, laterally spaced rows 16 and 17 and the mounting strip or base 15 is longitudinally translated through the apparatus 11 on an elongated bed, indicated generally at 18, by means of conveyor means indicated generally at 20. Although the strip 15 is described as longitudinally translated through the apparatus 11, it could, of course, be translated laterally if the apparatus 11 so provided. The apparatus 11 is driven by a motor 21, the moving portions thereof being connected to said motor by means of a clutch 22 connected to a transmission shaft 23. Other details of construction of the apparatus 11, per se, will not be discussed in detail herein and reference is made to the above referred to copending application for a more detailed description and discussion of the operation and structure of the apparatus.

The detecting device 10 is incorporated in a housing 25 which is mounted on a bed plate 26 secured to the frame 12 of the apparatus 11. Therefore, as best shown in Fig. 1 of the drawings, the detecting device 10 is disposed adjacent the bed 18 of the apparatus 11 upon which the mounting strip 15 is longitudinally translated by the conveyor means 20 during its passage through the apparatus 11 to facilitate the detection of the absence of fasteners 14 from the rows 16 and 17 of fasteners not inserted in the mounting strip 15 by the fastener feeding and inserting means 13 of the apparatus 11. It will be noted that the housing 25 of the device 10 is longitudinally spaced from the fastener feeding and inserting means 13 of the apparatus 11.

In order to detect the absence of one or more fasteners 14 from the mounting strip 15, fastener detecting means 27 are provided, as best shown in Figs. 2-5 of the drawings, said fastener detecting means 27 being constituted by elongated fingers or bars 29 and 30 mounted upon the extreme outer ends of arms 31 and 32. The elongated bar 29 engages the successive fasteners 14 of the row 16 of fasteners in the mounting strip 15, while the elongated bar 30 engages the fasteners 14 in the row 17 of fasteners in the mounting strip 15.

The elongated bars 29 and 30 are designed to span the distance between two fasteners in a row of fasteners, as best shown in Fig. 4 of the drawings. Therefore, as either of the bars 29 or 30 loses contact with a fastener 14 in the row, or shortly prior thereto, it engages the subsequent fastener in said row, preventing the bar from being moved upwardly, in a manner to be described in greater detail below, to indicate the absence of one or more fasteners from the row with which it is engaged. The ends of the arms 31 and 32 are rotatably mounted on a common pivot pin 35 which extends through the housing 25. Mounted in the housing 25 below the arms 31 and 32, respectively, are push rods 37 and 38, said push rods being disposed in bores 39 and 40, respectively, in the housing 25 and having their lower ends engaged by compression springs 41 and 42 which tend to bias them upwardly into engagement with the arms 31 and 32.

The push rods 37 and 38 thus serve to move the elongated fingers or bars 29 and 30 into a first position in which the bars engage successive fasteners 14 in the rows 16 and 17 of the fasteners in the mounting strip 15, as best shown in Fig. 2 of the drawings. However, when the absence of a fastener 14 occurs due to the failure of the feeding and inserting means 13 of the apparatus 11 to insert a fastener in predetermined order in the rows of fasteners 16 or 17, the appropriate finger 29 or 30 is moved upwardly into a second position, as best shown in Fig. 3 of the drawing wherein the finger 29 has been moved upwardly by the action of the push rod 37 and the compression spring 41 as applied to the elongated arm 31 to cause said arm to rotate about the pivot 35 and carry the finger 29 upwardly into the gap created by the absence of a fastener 14 in the row 16 of fasteners in the mounting strip 15. It should be noticed once again that the lengths of the fingers or bars 29 and 30 of the fastener detecting means 27 are sufficient to span the distance between two adjacent fasteners 14 in a row of fasteners, but are not sufficiently long to prevent their being moved upwardly into the gap caused by the absence of one or more fasteners in a particular row of fasteners.

The fastener detecting means 27 of the detecting device 10 constitutes the first detecting means of the invention and is disposed at a first station with respect to the bed 18 of the apparatus 11. This first station

is one below the plane of movement of the strip 15 through the apparatus 11, the fingers or bars 29 and 30 underlying the strip 15 and engaging the lowermost ends of the fasteners 14 which project therefrom and depend downwardly into contact with the fingers or bars 29 or 30.

Also to be noted is the specific configuration of the bars or fingers 29 and 30 and more particularly the configuration of the opposite ends 44 and 45 thereof, as best shown in Fig. 4 of the drawings. The ends 44 of the bars 29 and 30 are formed in the shape of inclined planes, as best shown in Figs. 2-4, so that when the first fasteners 14 of a row of fasteners engage the ends 44 of the bars in their normal passage through the apparatus 11, the fasteners will not be wedged thereagainst but will slide on the inclined planes to cause the bars 29 and 30 to be deflected downwardly to cause said bars to assume their first fastener engaging positions.

The opposite ends of the fingers or bars 29 and 30 are also provided with inclined planes at 45 so that when a mounting strip 15 is re-inserted from the delivery end of the bed 18 into the apparatus 11 to permit the apparatus to insert fasteners which have been missed during the initial passage of the mounting strip 15 through the apparatus, the fingers or bars 29 and 30 will have the inclined planes at their ends 45 engage the lowermost ends of the fasteners 14 to cause the bars 29 and 30 to ride downwardly with respect to the fasteners 14 and to prevent the wedging of the ends of the bars against the fasteners as the mounting strip 15 is fed into the bed 18 of the apparatus 11.

Incorporated in the housing 25 of the device 10 and constituting a portion of said device is an apparatus de-energization means 48, said apparatus de-energization means 48 being responsive to the detection by the bars or fingers 29 and 30 of the absence of one or more fasteners 14 from the mounting strip 15, in the above disclosed and discussed manner. The portion of the apparatus de-energization means 48 included in the housing 25 of the detecting device 10 includes an elongated lever arm 50, said arm being pivotally mounted intermediate its opposite ends on the pivot pin 35 and being disposed between the elongated arms 31 and 32 which mount the fingers 29 and 30 of the fastener detecting means 27. The elongated lever arm 50 thus constitutes the release means of the deenergization means 48 and is actuatable by the elongated arms 31 and 32 of the fastener detecting means 27 by means of a release pin 53 which is transversely secured in one end of the elongated lever arm 50 and engageable by the upper edges of either or both of the elongated arms 31 and 32 of the fastener detecting means 27.

As best shown in Fig. 4 of the drawings, the release pin 53 extends laterally of the one end of the elongated lever arm 50 in which it is mounted and spans the upper edges of the elongated arms 31 and 32. Therefore, as best shown in Fig. 3 of the drawings, when one or the other of the arms moves upwardly, in this particular instance the elongated arm 31 being shown in the second position in which the absence of a fastener 14 is detected, the upper edge of the elongated arm engages the transversely oriented release pin 53 to urge the one end of the elongated lever arm 50 in an upward direction.

A compression spring 55 is provided to urge the elongated lever arm 50 downwardly and has one end seated on the upper edge of said lever arm and its other end seated in a cavity provided in the interior of the housing 25. Thus, when the finger 31 is returned, in a manner to be described in greater detail below, to the first fastener detecting position, the spring 55 biases the elongated arm 50 downwardly into its lowermost position.

The other end of the elongated lever arm 50 constitutes a latch portion 57 and is engageable with an annular shoulder 60 provided on an elongated rod 61 which constitutes another portion of the apparatus de-energization means of the device. Mounted on the rod 61 externally of the housing 25 and having its opposite ends seated on collars 63 and 64 is a compression spring 65. The rod 61 can move freely through the collar 63 but the collar 64 is fixedly secured to the periphery of the rod 61. The rod 61, as best shown in Fig. 5 of the drawings, is longitudinally shiftable in a bore 67 in the housing by means of the spring 65 which is compressed between the collar 64 and the collar 63 when the latch

portion 57 of the elongated lever arm 50 engages the annular shoulder 60 on the rod 61.

Therefore, when one of the elongated arms 31 and 32 of the fastener detecting means 27 is moved upwardly by its associated push rod, due to the absence of one or more fasteners 14 from the mounting strip 15, and engages the transversely oriented release pin 53 in the elongated lever arm 50 to pivot the lever arm 50 about the pin 35 and move the latch portion 57 of the elongated lever arm 50 downwardly out of engagement with the shoulder 60 on the elongated rod 61, the spring 65 urges the rod 61 to the right in the direction of the arrow 69 of Fig. 1 to de-energize the apparatus 11 in a manner which will be described in greater detail below.

Supported upon and constituting a portion of the housing 25 is an auxiliary cylindrical housing 70, the housing 70 providing a support and partial enclosure for strip detecting means 75. Supported in the housing 70 is an elongated arm 77 which constitutes a portion of the strip detecting means 75 and has mounted in its outermost end the threaded shank 78 of a follower 80. The follower 80 is of frusto-conical configuration and its lower end is engageable with the upper surface of the mounting strip 15, as best shown in Figs. 2 and 3 of the drawings. The inner end of the elongated arm 77 is mounted for rotation with and upon an elongated latch pin 82 which is mounted centrally of the cylindrical housing 70 by means of a bore 83 in the upper end thereof and a bore 84 in the main housing 25. The cylindrical housing 70 includes an external shell 86 which is provided with a vertical slot 85 through which the elongated arm 77 projects, the shell 86 being rotatable with the arm 77 when it rotates with and upon the latch pin 82. Encompassing the periphery of the latch pin 82 and seated between the upper edge of the arm 77 and the inside wall of the top of the housing 70 is a compression spring 87, said spring tending to bias the arm 77 and its associated lock pin 82 downwardly into the position shown in dotted lines at 89 in Fig. 2 of the drawings wherein the lower end of the lock pin 82 engages the upper edge of the elongated lever arm 50 and wherein the frusto-conical cam follower 80 is disposed in the position shown by dotted lines at 90 in Fig. 2 of the drawings.

Provided in the base of the housing 70 is an annular cam 91, said cam being engageable by the lower edge of the elongated arm 77 and serving, when the arm 77 is rotated on and with the lock pin 82 in the shell 86, to raise the arm 77 and its associated follower 80 to permit the follower 80 to engage the upper surface of the mounting strip 15 which is being longitudinally translated along the bed 18 of the apparatus 11.

The basic function of the strip detecting device 75 is to prevent the actuation of the elongated lever arm 50 by either one of the arms 31 or 32 of the fastener detecting means 27 due to the absence of a mounting strip 15 at the station where the fastened detecting means 27 operates. When a mounting strip 15 is translated longitudinally on the bed 18 of the apparatus 11, the leading end thereof engages the frusto-conical cam follower 80 of the strip detecting means 75. The elongated arm 77 of the strip detecting means 75 is, at the time of contact with the leading end of the strip 15, disposed in the dotted line position shown in Fig. 5 of the drawings. The position of the arm 77 shown in full lines in Fig. 5 of the drawings constitutes the first strip engaging position of the arm and the arm is maintained in this position by means of a tension spring 94 which is connected between said arm and the bed 18 of the apparatus 11. When the arm 77 is disposed in the first strip engaging position shown in Fig. 5 of the drawings, the follower 80 mounted thereupon is disposed in a first, lowermost position shown at the dotted lines 90 in Fig. 2 of the drawings.

Therefore, the longitudinal movement of the leading end of the strip causes it to engage the follower 80 and to carry the follower 80 and its associated arm 77 in an arc between the first strip engaging position shown in Fig. 5 of the drawings and a second, temporary position of the arm 77 shown in dotted lines in said figure, against the tension of the spring 94. As the arm 77 is carried in the above described arc, the lower edge thereof engages the upper surface of the cam 91 and the arm 77 is carried upwardly on the cam 91 to raise the follower 80 from the first, lowermost position shown at 90 in Fig. 2 to a second, uppermost position in which it may engage the upper surface of the mounting strip 15. 85

As shown in Figs. 2 and 3, the follower is urged in the direction of movement of the strip 15 through the apparatus 11, as indicated by the arrow 95 in Fig. 5 of the drawings.

Although the action of the cam 91 is largely responsible for the upward movement of the follower 80 and its associated arm 77, the frusto-conical shape of the follower 80 prevents the follower from binding upon the leading end of the strip 15 and serves, also, to urge it upwardly to augment the upward movement imparted thereto by the lifting action of the cam 91. When the follower 80 has been urged into the second position shown in dotted lines in Fig. 5 of the drawings by the leading end of the strip 15, it has also been raised by the cam 91 and the arm 77 into the second uppermost position shown in full lines in Fig. 1 of the drawings where it engages the upper end of the strip. When such engagement occurs, the tension spring 94 snaps the arm 77 back into the first position shown in full lines in Fig. 5. 20 When so disposed, the follower 80 is located at a station immediately in advance of the fastener detecting means 27 so that the absence of a strip 15 from the bed 18 will permit the follower 80 to drop into its first, lowermost position to prevent the energization of the fastener detecting means 27. During the movement of the strip 15 through the apparatus 11, the arm 77 and the follower 80 are thus maintained, respectively, in the first position and the second, uppermost position.

Thus, should a gap occur between the ends of strips 30 15 being fed through the apparatus 11, as best shown in Fig. 1 of the drawings, when the trailing end of the strip 15 reaches the follower 80 in its first and second uppermost positions, the follower 80 will drop from engagement with the upper surface of the strip 15 so that 35 it will move from its second, uppermost strip contacting position into the first lowermost position indicated by the dotted lines 90 in Fig. 2 of the drawings.

When this occurs, the downward movement of the arm 77 is accompanied by downward movement of the locking pin 82 which then rides into engagement with the upper edge of the elongated lever arm 50. However, when the trailing edge of the strip 15 has passed over the fingers or bars 29 and 30, the normal tendency 40 thereof is to move upwardly since they are no longer in contact with fasteners 14 mounted in said strip. The locking pin 82 effectively prevents such upward movement of the fingers or bars 29 and 30 by restraining the elongated lever 50 from upward movement, through its contact with the upper edge of the lever 50 and the engagement of the release pin 53 mounted in said lever 45 with the upper edges of the arms 31 and 32 upon which the fingers 29 and 30 are supported.

Therefore, the strip detecting means 75 prevents the inadvertent actuation of the apparatus de-energization 55 means 48 of the device when a strip 15 is not positioned with its fasteners incorporated therein at the point along the bed at which the fastener detecting means 27 is located. It should be noted in passing that the strip detecting means 75 is positioned at a second station with respect to the bed 18 which overlies the fastener detecting means 27 and the strip 15 as it is longitudinally translated through the apparatus 11. However, once the following strip 15 engages the follower 80 of the strip detecting means 75 and the follower 80 has been returned to its first position shown in full lines in Fig. 5 of the drawings, the locking pin 82 is moved upwardly into its second, uppermost position in conjunction with the arm 77 and the follower 80, thus freeing the upper edge of the locking lever 50 for movement by the arms 31 and 32 of the fingers 29 and 30 of the fastener detecting 60 means 27.

As previously indicated, when the absence of one or more fasteners is detected by the fingers or bars 29 or 30 of the fastener detecting means 27, the latch portion 57 of the lever arm 50 is moved downwardly to release the annular shoulder 60 on the rod 61 permitting the rod 61 to be urged to the right, as shown in Fig. 1 of the drawings, by the action of the compression spring 65. The elongated rod 61 has the end opposite to that mounted in the housing 25 mounted in an end block 97 on the 75 frame 12 of the apparatus 11. The end of the rod 61 adjacent the end block 97 is connected to a substantially T-shaped lever 98 which is pivotally mounted upon the frame 12 of the apparatus at 99 by one leg thereof, the other leg 100 engaging one end of a pivotally mounted handle 102 which has secured intermediate its ends a 80 85

vertically disposed push rod 103. The lowermost end of the push rod 103 is secured to a bellcrank 105, said bellcrank being connected to the throw-out lever 106 associated with the clutch 22. Thus, when the rod 61 which constitutes a portion of the de-energization means of the device 10 is shifted to the right, as best shown in Fig. 1 of the drawings, the lever 98 is pivoted at 99 upon the end of the rod causing the other arm 100 thereof to be raised against the end of the handle 102. The upward pivotal movement of the handle 102 causes the concomitant vertical translation of the push rod 103, moving the bellcrank 105 in an arc to rotate the throw-out lever 106 to throw out the clutch and thus sever the driving-driven relationship between the motor 21 and the shaft 23.

In this manner, the detection of the absence of one or more fasteners from a mounting strip 15 by the fastener detecting means 27 of the device 10 automatically de-energizes the apparatus 11 through the de-energization means of the device 10 and immediately causes the cessation of the longitudinal translation of the strip 15 through the apparatus 11.

After the device 10 has indicated the absence of one or more fasteners 14 from the strip 15 by shutting down the apparatus 11, the strip 15 can be removed from the bed 18 and recirculated therethrough at a later time with a plurality of similarly defective strips or, it can be refed onto the bed 18 to permit the missing fastener to be inserted therein. To initiate the operation of the apparatus 11 after the detection of an imperfect strip 15, the handle 102 is depressed. When this occurs, the rod 103 moves downwardly, the bellcrank 105 is rotated and the throw-out lever 106 is pivoted to throw in the clutch 22 to establish a driving-driven relationship between the motor 21 and the shaft 23. The downward movement of the handle 102 causes the concomitant downward movement of the other portion of the crossbar 100 of the T-shaped lever 98 which pivots at 99 and causes the longitudinal translation of the elongated rod 61 to the left, as best shown in Fig. 1 of the drawings. When the longitudinal translation of the rod to the left occurs, the spring 65 is compressed between the collars 63 and 64 and the shoulder 60 of the rod 61 is brought into registry with the latch portion 57 of the elongated lever arm 50. Due to the action of the spring 65, the latch portion 57 is urged upwardly into engagement with the shoulder 60 and the downward movement of the pin 53 in the end of the lever 50 causes the concomitant downward movement of the arms 31 and 32 upon which the bars 29 and 30 of the fastener detecting means 27 are supported. In this manner, the device 10 and the apparatus 11 are simultaneously energized and the device 10 and apparatus 11 are once again ready to operate upon the mounting strip 15 passing through the apparatus 11.

There is provided by the invention a detecting device which is designed to automatically ascertain the absence of one or more fasteners from a mounting strip passing through a fastener securing apparatus. Also incorporated in the detecting device is a fastener detecting means which discerns the absence of one or more fasteners from the strip and a strip detecting means which discerns the absence of a strip from the bed of the apparatus with which the device is associated or the existence of a gap between a leading and following strip. Incorporated in the strip detecting means is lock means designed to prevent the actuation of the fastener detecting means when such actuation would be caused by the absence of a strip from the apparatus.

Also found in the device of the invention is apparatus de-energization means actuatable by the fastener detecting means upon the detection by said fastener detecting means of the absence of one or more fasteners from a strip. Other advantages and advances of the invention and the device embodying said invention can be found by resort to the above specification.

I claim as my invention:

1. In a device for detecting the absence of fasteners from a base strip in which fasteners are normally secured, the combination of: first detecting means engageable with fasteners in said strip for detecting the absence of fasteners from said strip; and second detecting means placed ahead of said first detecting means and operatively engageable with said first detecting means for preventing the operation of said first detecting means when said strip is moved beyond said second detecting means.

2. In a device for detecting the absence of fasteners from a base strip in which fasteners are normally secured during the movement of said base strip through a fastener inserting apparatus, the combination of: first detecting means engageable with fasteners in said strip for detecting the absence of fasteners from said strip during its movement through said apparatus, said first detecting means including finger means movable into engagement with said fasteners; and second detecting means placed ahead of said first detecting means and operatively engageable with said strip for preventing the operation of said first detecting means when said strip is moved beyond said second detecting means.

3. In a device for detecting the absence of fasteners from a base strip during the movement of said strip through an apparatus which inserts fasteners therein, the combination of: first detecting means engageable with fasteners in said strip for detecting the absence of fasteners from said strip; second detecting means placed ahead of said first detecting means and operatively engageable with said strip for preventing the operation of said first detecting means when said strip is moved beyond said second detecting means in said apparatus; and deactuation means for preventing the operation of said apparatus operable by said first detecting means when said first detecting means is operated by the absence of a fastener from said strip.

4. In a device which is operatively associated with an apparatus for inserting fasteners into a mounting strip to detect the absence of one or more fasteners from said strip subsequently to the insertion of fasteners by said apparatus, the combination of: a bed for supporting said strip during movement through said apparatus; conveyor means operatively engageable with said strip for causing the longitudinal translation thereof through said apparatus; first detecting means engageable with fasteners in said strip for detecting the absence of a fastener from said strip; and second detecting means disposable in advance of said first detecting means adjacent said bed for detecting the absence of said strip from said bed to prevent the actuation of said first detecting means due to the absence of said strip from said bed.

5. In a device responsive to the absence of fasteners from a fastener mounting base strip, said device being associated with an apparatus for inserting fasteners in said strip, said apparatus including an elongated strip supporting bed and conveyor means for longitudinally translating said strip along said bed, the combination of: strip detecting means mounted adjacent said bed and engageable with said strip for determining the presence of said strip on said bed; and fastener detecting means mounted adjacent said bed and engageable with fasteners in said strip, said fastener detecting means being operatively engageable by said strip detecting means to prevent the operation of said fastener detecting means when said strip detecting means is actuated by the absence of said strip from said bed.

6. In a device responsive to the absence of fasteners from a fastener mounting base strip, said device being associated with an apparatus for inserting fasteners in said strip, said apparatus including an elongated strip supporting bed and conveyor means for longitudinally translating said strip along said bed, the combination of: strip detecting means mounted adjacent said bed and disposable at a first station, said strip detecting means being engageable with said strip and responsive to passage of said strip beyond said first station; and fastener detecting means mounted adjacent said bed at a second station spaced from said first station, said fastener detecting means being engageable with fasteners in said strip to detect the absence of a fastener from said strip and being operatively engageable by said strip detecting means to prevent the actuation of said fastener detecting means because of the absence of a strip from said bed.

7. In a device for detecting the absence of fasteners from a fastener mounting base strip during its movement along the bed of a fastener inserting apparatus, the combination of: strip detecting means mounted adjacent said bed at a first station, said strip detecting means including a follower engageable with said strip and responsive to the completed passage of said strip along said bed; and fastener detecting means mounted adjacent said bed at a second station, said fastener detecting means being operatively engageable by said strip detecting means to prevent the actuation of said fastener detecting means

due to the completed passage of a strip through said apparatus.

8. In a device for detecting the absence of fasteners from a fastener mounting strip during its passage along the bed of a fastener inserting apparatus, the combination of: a housing mounted adjacent said bed; strip detecting means secured in said housing and movable by the passage of a strip along said bed, said strip detecting means including a follower engageable with said strip; fastener detecting means mounted in said housing including fastener engaging fingers for detecting the absence of one or more fasteners from said strip; and deactuation means operable by said fastener engaging fingers when said fastener engaging fingers detect the absence of one or more of said fasteners from said strip to deactivate said apparatus, said deactuation means being engageable by said strip detecting means to prevent the operation of said deactuation means when said strip detecting means responds to the completed passage of a strip through said apparatus.

9. In a device which is operatively associated with an apparatus for inserting fasteners into a mounting strip to detect the absence of one or more fasteners from said strip subsequently to the insertion of fasteners by said apparatus, the combination of: an elongated bed; a conveyor means for translating an elongated mounting strip along said bed; a strip detector mounted adjacent said bed, said strip detector including an elongated, movable arm and a strip contacting follower mounted upon said arm, said arm having fastened thereto latch means responsive to movement of said follower in a vertical plane; fastener detecting means mounted adjacent said bed and spaced from said strip detector; and deactuation means operable by said fastener detecting means when said fastener detecting means detects the absence of one or more fasteners from said strip, said latch being movable into engagement with said deactuation means to prevent the actuation thereof by said fastener detecting means when said strip detecting means moves out of contact with a strip subsequently to the passage of said strip through said apparatus.

10. In a device which is operatively associated with an apparatus for inserting fasteners into a mounting strip to detect the absence of one or more fasteners from said strip subsequently to the insertion of fasteners by said apparatus, the combination of: a bed for receiving said strip; conveyor means for conveying said strip along said bed; a strip detector mounted adjacent said bed, said strip detector including a movable follower operatively connected to a movable lock; a fastener detector mounted adjacent said bed in spaced relation with said strip detector, said fastener detector including fastener engaging fingers for ascertaining the absence of one or more fasteners from said strip; and release means mounted adjacent said bed in operative relation with said strip detector and said fastener detector, the movement of said strip detector from a second strip releasing position to a first strip engaging position causing the movement of said lock out of operative engagement with said release means to allow actuation thereof by the fastener detector means.
20. 11. In a device designed to detect the absence of fasteners from a mounting strip during the translation of said strip through a fastener driving apparatus, the combination of: a housing; a strip detector mounted in said housing for longitudinal movement between a strip engaging position and a strip releasing position and for movement between a first unlocked position and a second locked position; fastener detecting means mounted in said housing for movement between a fastener engaging position and a fastener absence detection position; and release means operative by said fastener detecting means and engageable by said strip detector to prevent the actuation of said release means by said fastener detecting means when said strip detector detects the absence of a strip from said apparatus.
